UNITED STATES PATENT OFFICE.

FREDERICK R. HIRSH, OF NEW YORK, N. Y.

DESIGN FOR A PLATE FOR HARDWARE.

SPECIFICATION forming part of Design No. 24,783, dated October 22, 1895.

Application filed June 26, 1895. Serial No. 654,152. Term of patent 7 years.

To all whom it may concern:

Be it known that I, FREDERICK R. HIRSH, a citizen of the United States, and a resident of the city of New York, in the county and State of New York, have invented and produced a new and original Design for a Plate, of which the following is a specification, reference being had to the accompanying drawing, forming a part thereof.

10 The drawing is a front view of a plate, showing my design.

The leading features of my design consist of a panel, a bed of Romanesque leaves located at each end of the panel, and a vermiform band having loops and circles surrounding the panel and interlaced or coiled over the leaves.

Particularly describing my design, it comprises a panel, and at one end of the panel a Romanesque leaf surrounded by an interlaced

20 vermiform band in such manner that the band forms two smaller circles, in the center of which is seen the leaf, and outside of these two circles and coincident with their outer

periphery is a larger semicircle formed of the same band. Exterior to the small circles containing the leaf are loops formed by the band, and outside of the semicircle formed by the band are other leaves. Connecting the ornamentation at one end of the plate with the ornamentation at the other end of the plate is 25 the band continuing along the sides of the plate. At the opposite end of the plate to that already described the band forms a finish at the edge and is continued and interlaced so as to form a triangle of three small circles 30 35 looped together. Beneath the circles is another bed of Romanesque leaves.

Having thus described my invention, the following is what I claim as new therein and desire to secure by Design Letters Patent: 40

The design for a plate; substantially as herein shown and described.

FREDERICK R. HIRSH.
